UNITED STATES PATENT OFFICE

FRED C. EASTMAN, OF BEVERLY, MASSACHUSETTS, ASSIGNOR TO UNITED SHOE MACHINERY CORPORATION, OF PATERSON, NEW JERSEY, A CORPORATION OF NEW JERSEY

FASTENING-INSERTING MACHINE

Application filed October 23, 1928, Serial No. 314,468, and in Great Britain August 1, 1928.

This invention relates to fastening inserting machines and is illustrated herein as embodied in a power driven fibre-peg inserting machine, the peg inserting instrumentalities of which are contained in a housing arranged to be grasped by the hand of the operator and to be moved peripherally of the heel or toe portion of a shoe mounted on a last in a bed lasting machine to insert pegs through the upper and into the insole of the shoe to secure the upper in lasted relation to the insole.

When inserting fibre pegs to secure together the parts of shoe bottoms it is particularly desirable that the length of the pegs be varied in accordance with the thickness of the parts of the shoe bottoms into which they are inserted. This gives each peg the maximum holding power and, when the pegs are driven into a thin insole, it may be necessary in order to insure that the pegs do not pull out of the insole. As a shoe ready for the operation of a bed lasting machine is mounted upon a last, its bottom cannot be calipered, as might be done if it were off the last. Until the present invention there was no mechanism known to me which could be utilized to measure the thickness of a shoe bottom while the shoe was on the last thereby to control the length of the fastenings inserted.

It is an object of the present invention to provide fastening inserting mechanism having means for measuring the thickness of the bottom of a shoe mounted upon a last and means for inserting in the bottom of the shoe fastenings the lengths of which correspond to the measured thickness of the shoe bottom.

In accordance with this object and with a feature of the invention, the illustrated machine is provided with an awl and operating means therefor of such a nature that the awl can be driven through the bottom of a shoe mounted upon a last and arrested by striking a metal plate upon the bottom of the last without interfering with the normal operation of the machine and without danger of breaking the awl or its operating mechanism. Thus the length of the stroke of the awl is dependent upon the thickness

of the stock which the awl penetrates and the length of the awl stroke is utilized to control the length of the fastenings inserted in the holes formed by the awl.

In accordance with another feature of the invention the awl operating means of the illustrated machine includes an awl bar or carrier, and a connection between the awl bar and means for reciprocating the awl bar which connection is broken when the awl meets an excessive resistance during its work-penetrating stroke but which is remade later in the cycle of operation so that the awl bar is picked up and the awl is withdrawn from the shoe bottom. Thus the cycle of operation of the machine is completed as it would have been if the stock into which the awl was thrust was thick enough so that the awl did not pass entirely through it and the machine is ready to operate through another cycle. The fastenings inserted by the illustrated machine are severed from a strip of fastening material, for example paper twine, commonly called fiber-fastening material, which is fed intermittently by mechanism controlled by the movement of the awl bar so that each fastening severed from the strip is of a length determined by the distance which the awl penetrates the work before it is stopped by striking the metal bottom plate of the last in each cycle of the machine. Thus it will be seen that the awl actually measures the thickness of the shoe bottom and that each of the fastenings inserted in the holes formed by the awl is of a length corresponding to the thickness of the portion of the stock into which it is inserted.

A further feature of the invention, as embodied in the illustrated machine, consists in driver operating mechanism comprising a continuously reciprocating member, a driver operating member, and connections between the two members arranged to be made and broken by a manually operable controller so that the driver operating member can be driven intermittently, at the will of the operator, by the continuously reciprocating member. This construction reduces to a minimum the weight of the parts which must be set in motion and stopped each time that the fas-

tening inserting means is started and stopped.

While the invention is illustrated herein as embodied in a fastening inserting machine intended to take the place of the hand tackers commonly used with bed lasting machines, it is clear that the invention is not limited in its utility to embodiment in fastening inserting machines of that type and, accordingly, the construction disclosed herein should be regarded primarily as an illustration of one of the forms in which my invention may be embodied.

With the above and other objects and features in view the invention will now be described with reference to the accompanying drawings and pointed out in the claims.

In the drawings,

Fig. 1 is a side elevation, partly in section, of a fastening inserting machine embodying the invention;

Fig. 2 is a similar view of the fastening instrumentalities of the machine, on a larger scale, showing the parts in the position which they occupy at the conclusion of the punching of a fastening receiving hole in the work piece;

Fig. 3 is a view similar to Fig. 2, showing the position of the parts at the end of the feeding of the strip of fastening material preparatory to the severing of a fastening therefrom;

Figs. 4 and 5 show the position of the parts at the beginning and at the end respectively of the driving of a fastening; and

Figs. 6 and 7 illustrate connections by means of which the length of the punching or awl stroke and the length of the fastening severed from the strip are controlled in accordance with the thickness of the shoe parts through which the fastening is to be driven.

The illustrated fastening inserting machine is intended to take the place of the hand tackers commonly used in lasting the toes of McKay shoes and the heel portions of Goodyear welt, McKay and other types of shoes. In order to avoid the objections incidental to the use of tacks to secure shoe uppers in lasted position, the illustrated machine is arranged to insert fibre pegs of the character disclosed in Letters Patent of the United States No. 1,729,169 granted September 24, 1929, on an application filed in the name of Fred N. LaChapelle. These pegs are severed from a strip of fibre peg material such as paper twine and inserted in holes punched by the machine through the shoe upper into the insole.

The fastening-inserting instrumentalities of the machine are carried at the end of an arm 10 counterbalanced by a weight W and pivoted at 12, for vertical swinging movement, to a bracket 14 mounted for horizontal swinging movement at the top of a column 16 so that the fastening-inserting instrumen-

talities can readily be presented to the different parts of a shoe to secure the toe and heel portions of the shoe upper in lasted relation to the insole and last. The column 16, which carries also a reel 18 containing a supply of the peg material 19, may conveniently be secured to a bed lasting machine. The bracket 14 carries also a motor 20 geared, as shown at 22, to a cam member 24 provided with a pair of cam tracks 26, 28. In these cam tracks are positioned a pair of rolls 30, 32 carried respectively by slide blocks mounted for longitudinal sliding movement in ways formed in the arm 10 and pivoted at 34, 36 respectively to longitudinally movable rods 38, 40 extending lengthwise of the arm 10 and pivoted respectively at their right-hand ends to a pair of bell crank levers 42, 44 fulcrumed at 46, 48 to an arm 50 carried by the right-hand end of the arm 10 and serving to operate the fastening-inserting instrumentalities. The bell crank lever 44 is rocked twice and the lever 42 once during each revolution of the cam member 24.

Depending from the lower end of the arm 50 is a tube 52 carrying at its lower end a housing 54 which contains the fastening severing and inserting portions of the machine. Within the tube 52 is a sleeve 56 utilized to operate the fastening severing means and carrying at its upper end a collar 57 provided with a pair of slots which receive pins 58 carried by the bifurcated end of the bell crank lever 42 so that rocking of the bell crank lever 42 about its fulcrum 46 will reciprocate the sleeve 56. Within the sleeve 56 is a rod 60 carrying a tool 104 which acts both as an awl and as a driver. To the upper end of the rod 60 is clamped a collar 62 to which is pivoted a depending latch member 64 urged in a clockwise direction, as viewed in the various figures of the drawings, by a spring 66. The latch member 64 is provided with an approximately horizontal shoulder 68 (Figs. 1 and 6) engaging a complementary shoulder 70 formed upon a shorter latch member 72 pivoted at 74 to a sleeve 76 surrounding the rod 60 and forming a guide for the upper end of the rod. The sleeve 76 is provided with a pair of horizontal slots entered by a pair of pins 78 carried by the bifurcated end of the bell crank lever 44.

When the motor 20 is running the bell crank levers 42 and 44 are continuously oscillated, but when the machine is not in use the sleeve 76 slides idly up and down on the rod 60 and the fastening-inserting instrumentalities are inoperative since the latch 64 is held disengaged from the latch 72, as shown in Fig. 1. To hold the latch members 64 and 72 disengaged while the machine is not in operation the latch member 64 is provided with a finger 80 extending toward the left and engaged by a latch member 82 having the form of a bell crank lever fulcrumed at 84 to 100

an extension 86 of the arm 50. The latch member 82 has a rearwardly extending arm 88 secured to a stiff wire 90 passing downwardly and secured at its lower end to a forwardly extending arm 92 (Fig. 2) of a manually operable controller illustrated as a trigger 94 fulcrumed at 96 to a hand grip 98 secured to the housing 54 and by which the housing can conveniently be grasped and moved peripherally of the heel or toe portion of a shoe mounted on a last in a bed lasting machine. The trigger 94 is urged in a clockwise direction by a spring 100, thus tending to hold the latch 82 in the position shown in Fig. 1, under which circumstances the shoulders 68, 70 of the latch members 64, 72 are disengaged. A pin 102, extending through the extension 86, limits the movement in a clockwise direction of the latch member 82. When the operator squeezes the trigger 94, as illustrated in Fig. 2, the latch member 82 is moved in a counterclockwise direction, as indicated in dotted lines in Fig. 3, releasing the finger 80 of the latch member 64 so that the latter is rotated by its spring 66 to bring its shoulder 68 into such position that when the latch member 70 reaches the upper end of its reciprocating movement the shoulder 68 can pass beneath the shoulder 70 of the latch member 72, latching the two together. Subsequent downward movement of the sleeve 76 is thus operative to move the rod 60 downwardly, as shown in Fig. 2.

The rod 60 serves as a carrier for the tool 104 which is reciprocated through a throat or nozzle 105, acting both as an awl and as a driver, and which, as a matter of convenience, is hereinafter spoken of either as an awl or as a driver, according to the function under consideration. In Fig. 2 the tool 104 is shown acting as an awl to punch a hole through the various layers 106 of a shoe upper and insole mounted upon a last 108 provided with a metal bottom plate or heel plate 110. When the awl 104 hits the metal plate 110 the excessive resistance arrests the rod 60 and it can no longer move downwardly. This takes place before the completion of the first downward movement of the outwardly extending arm of the bell crank lever 44 in each cycle of operation of the machine. Thereafter the continued movement of the bell crank lever 44, which, it is to be remembered, is connected by pin-and-slot connection to the sleeve 76, is effective to rock the latch member 72 about its pivot 74 in a counterclockwise direction against the compression of a spring 112 surrounding a pin 114 carried by the sleeve 76 and bearing at one end against the lower end of the latch member 72 and at the other end against a nut 116 threaded on the pin 114. As the lower end of the latch member 72 engages the lower end of the longer latch member 64, this rocking movement of the latch member 72 is effective also to rock

the latch member 64 against its spring 66, pushing or dragging the shoulder 68 out from under the shoulder 70 and thus breaking the driving connection to the awl 104, after which the latch member 72 and the sleeve 76 are free to continue their downward movement while the rod 60 remains at rest. It will be seen that the extent of the downward movement of the awl 104 is dependent upon the thickness of the shoe parts which bear against the nozzle 105 and which are backed up by the metal plate 110 of the last 108. Thus, the work penetrating movement of the awl 104 is effective to measure the thickness of the shoe bottom parts into which it is thrust.

The extent of this movement of the awl 104 is utilized to measure the length of the fastening severed from the strip 19 of fastening material, for example paper twine, carried by the reel 18. The strip 19 passes through a vertical guide tube 122 extending upwardly at the right-hand end of a block 124 clamped to the lower end of the tube 56. Below the tube 122 the guide block 124 is provided with a depending portion having a surface 126 (Fig. 3) past which the strip 19 passes. Opposed to the surface 126 is a dog 128 also arranged to bear against the strip 19 and pivoted to the end of a bell crank lever 130 which is fulcrumed at 132 to the depending portion of the block 124. The bell crank lever 130 is urged in a counterclockwise direction by a spring 134 and its upwardly extending arm carries a projection 136 (Fig. 2) bearing against the rod 60 and arranged to enter a groove 138 formed in the rod 60 just before the conclusion of the down stroke of the rod. The distance from the projection 136 to the lower end of the groove 138 at the conclusion of the work-penetrating movement of the awl 104 will, of course, depend upon the thickness of the stock between the nozzle 105 and the metal plate 110 of the last. The feeding of the strip of fastening material is caused by sliding the block 124 downwardly along the rod 60 while the latter is held stationary at the termination of the work-penetrating movement of the awl 104, the strip 19 being gripped between the dog 128 and the surface 126 as the block 124 is moved downwardly until the projection 136 reaches the lower end of the groove 138. When this takes place, further downward movement of the block 124 causes the lower end of the groove 138 to cam the projection 136 of the lever 130 to the right, rocking the lever 130 in a clockwise direction, as viewed in the various figures, and thus relieving the pressure of the dog 128 on the strip 120 and terminating the feeding of the strip. The block 124 is given this downward movement by the cam 24, the motion being transmitted by the rod 38, the bell crank lever 42 and the sleeve 56.

To prevent retrograde movement of the strip 19, the latter passes beneath a second dog 140 pivoted to the end of a lever 142 fulcrumed at 144 to the housing 54. A spring 146 tends to rock the lever 142 in a counter-clockwise direction, thus gripping the strip between the dog 140 and a stationary surface 148. Feeding movement of the strip 19 rocks the lever 142 slightly against the action of the spring 146, relieving the pressure of the dog 140 on the strip. Retrograde movement of the strip 19 has the opposite effect and any tendency thereto results in gripping the strip firmly between the dog 140 and the surface 148.

From the dog 140 the strip 19 of fastening material passes through a stationary tube 150 the lower end of which is supported by a stationary block 152 carried near the lower end of the housing 54. The severing of pegs from the strip 19 of fastening material is accomplished by rocking movement of a bell crank lever 156 fulcrumed upon a stationary pin 158 extending transversely through the housing 54 and provided with a passage 160 (Fig. 3) through which the tool 104 may pass. The bell crank lever 156 is provided with a passage 162 which at the time of the feeding of the fastening is in alignment with the tube 150 and also with a second passage which is in alignment with the tool 104 at all times when the lower end of the latter is closely adjacent to or below the intersection of its path of movement with the upper surface of the bell crank lever 156. The metal at the inlet end of the passage 162 and at the outlet of the hole in the block 152, which hole serves as a continuation of the tube 150, serve to shear a peg from the strip 19 as the bell crank lever 156 is rocked.

After the fastening material has been fed, the rod 60 is moved upwardly, withdrawing the awl 104 to a position above the bell crank lever 156. The bell crank lever 156 is then rocked in a counterclockwise direction from the position shown in Fig. 1 to the position shown in Fig. 4, thus severing a fastening and bringing it into position to be driven. This is accomplished by further downward movement of the sleeve 76 which brings the block 124 into engagement with a collar 170 secured to a rod 172 the upper end of which is guided by the block 124 and the lower end by the block 152. At its lower end the rod 172 is pivoted to the bell crank lever 156. A compression spring 176 engages at its upper end against the collar 170 and at its lower end against the block 152, thus serving to maintain the bell crank lever 156 in the position shown in Figs. 1, 2 and 3 except when the rod 172 is depressed by the block 124. In order that the fastening receiving position of the bell crank lever 156 may be accurately maintained, a stationary shoulder 178 is carried by the housing 54 at the right-

hand end of the path of movement of the upper end of the bell crank lever 156.

After the bell crank lever 156 has been rocked to bring the fastening into the line of drive, the rod 60 is again moved downwardly by rotation of the cam member 24 until the end of the driver 104 is substantially flush with the end of the nozzle 105. This movement does not bring the groove 138 into engagement with the projection 136 of the bell crank lever 130 which carries the feeding dog 128. During the driver stroke, moreover, the shoulders 68, 70 of the latch members 64, 72 have no tendency to disengage since the form of the cam groove 28 is such that the sleeve 76 is not moved downwardly after the driver 104 comes to rest.

After return movement of the rod 60 at the conclusion of the driver stroke, the machine will start upon a new cycle of operation if pressure is maintained upon the trigger 94. If, however, the trigger 94 is released before the conclusion of the cycle, the latch member 82 will move into position to engage the finger 80 of the latch member 64 just before the conclusion of the upward stroke of the rod 60 and will cause the latch member 64 to swing to the position shown in Fig. 1 in which it is released from the latch member 72 so that the machine will cease to operate.

When operating the illustrated machine the operator grasps it by the handle 98, bringing the nozzle 105 into position on the shoe bottom or other work piece into which a fastening is to be inserted, and then presses the trigger 94 to cause the operation of the device. The movement of the trigger is effective through the connection 90 to swing the latch 82 from the position shown in Fig. 1 to the position shown in Fig. 2, thus releasing the finger 80 and permitting the latch member 64 to move into the position shown in Fig. 2 in which its shoulder 68 engages beneath the shoulder 70 of the latch member 72. When this takes place the sleeve 76, which is reciprocated continuously by the motion transmitted from the motor 20 through the cam 28, the rod 40 and the bell crank lever 44, causes the rod 60 to move downwardly thus thrusting the awl 104 forcibly into the work piece. When the end of the awl strikes the metal bottom plate 110 of the last 108 the awl can pass no further. Continued downward movement of the sleeve 76 is then effective to rock the latch members 72 and 64 in the manner shown in Fig. 6, thus releasing the shoulder 68 of the latch member 64 from the shoulder 70 of the latch member 72 so that the sleeve 76 can continue its downward movement. Upon subsequent upward movement of the sleeve 76 its upper end engages the collar 62 which is clamped to the rod 60 and lifts the latter, withdrawing the awl from the work piece. Subsequent to the downward movement of the rod 60 the block 124 and the bell

crank lever 130 are moved downwardly by the sleeve 56, feeding the fastening material 19 downwardly till the projection 136 of the bell crank 130 reaches the lower end of the 5 slot 138.

The length of the fastening subsequently severed is determined by the extent of movement of the sleeve 56 and the bell crank lever 130 before the projection 136 of the bell crank 10 lever 130 is cammed to the right by the lower end of the groove 138 formed on the rod 60 and the feed dog 128 is rendered inoperative. Thus the length of the fastening is determined by the thickness of the work piece into 15 which it is to be inserted. A second downward movement of the rod 60 is effective to cause the tool 104 to drive the fastening through the nozzle 105 into the work piece.

This action is continued cyclically as long 20 as the trigger 94 is pressed toward the handle 98. When the trigger is released the machine completes the cycle of operation upon which it is engaged and at the end of the cycle the finger 80 is rocked in a counterclockwise direction by engagement with the end of the latch member 82, thus withdrawing the shoulder 68 of the latch member 64 from the shoulder 70 of the latch member 72 and causing the rod 60 to come to rest.

30 Having thus described my invention, what I claim as new and desire to secure by Letters Patent of the United States is:—

1. A fastening inserting machine having, in combination, means for measuring the 35 thickness of the bottom of a shoe mounted on a last, and means for inserting in the bottom of the shoe fastenings of a length corresponding to the measured thickness of the shoe bottom.

40 2. A fastening inserting machine having, in combination, means for measuring the thickness of the bottom of a shoe mounted on a last, means for severing from a strip of fastening material a fastening of a length 45 corresponding to the measured thickness of the shoe bottom, and means for driving said fastening in the shoe bottom.

3. A fastening inserting device having, in 50 combination, fastening inserting mechanism, means for measuring the thickness of the bottom of a shoe mounted upon a last, and means for operating the fastening inserting mechanism to insert in the bottom of the shoe fastenings the lengths of which correspond to the measured thickness of the shoe bottom.

55 4. A fastening inserting device having, in combination, an awl, means for reciprocating the awl constructed and arranged to cause the 60 awl to penetrate the bottom of a shoe mounted upon a last and to come to rest when the awl strikes the bottom of the last, and means for inserting in the holes formed by the awl fastenings of a length determined by the distance which the awl moves while passing

through the work when forming the holes for the respective fastenings.

5. A fastening inserting machine having, in combination, an awl, and means for reciprocating the awl constructed and arranged to cause the awl to penetrate a work piece presented thereto and to come to rest in each cycle of operation when it meets an excessive resistance, said means being arranged to withdraw the awl from the work 70 later in the cycle of operation of the machine, and means for inserting in each hole formed by the awl a fastening the length of which is determined by the depth to which the awl penetrated the work piece in forming that hole.

6. A fastening inserting machine having, in combination, an awl, a cam, connections between the cam and awl constructed and arranged to thrust the awl forcibly into a 85 work piece presented thereto but to permit the awl to come to rest in each cycle of operation when it meets an excessive resistance, and later in the cycle to withdraw the awl from the work, and means for inserting a 90 fibre peg in the hole formed in the work piece by the awl.

7. A fastening inserting machine having, in combination, an awl, means for reciprocating the awl constructed and arranged to 95 cause the awl to penetrate the bottom of a shoe mounted on a last and to come to rest when the awl strikes the bottom plate of the last, said means including a connection which is broken when the awl hits the bottom 100 plate of the last.

8. A fastening inserting machine having, in combination, an awl, and means for reciprocating the awl constructed and arranged to cause the awl to penetrate the bottom of a shoe mounted on a last and to come to rest when the awl strikes the bottom plate of the last and thereafter to be withdrawn, said means including a connection which is 105 broken when the awl hits the bottom plate 110 of the last.

9. A fastening inserting machine having, in combination, fastening inserting instrumentalities including an awl, means for reciprocating the awl to form fastening receiving holes in a work piece constructed and arranged to cause the awl to come to rest when it meets an excessive resistance, and means for inserting in the holes formed by the awl fastenings the lengths of which are 115 determined by the length of the path of movement of the awl when forming the holes in which the respective fastenings are 120 inserted.

10. A fastening-inserting machine having, 125 in combination, an awl, means for reciprocating the awl through a path the length of which depends upon the thickness of the work piece presented to the machine as measured by the awl at the point where a fasten- 130

- ing is to be inserted constructed and arranged to cause the awl to come to rest when it has passed completely through the work piece, and means for inserting in the holes formed in the work piece by the awl fastenings the lengths of which are determined by the lengths of the paths measured by the awl when forming the holes in which the respective fastenings are inserted.
11. A fastening inserting machine having, in combination, an awl, and means for reciprocating the awl constructed and arranged to thrust the awl forcibly into the bottom of a shoe mounted on a last having an impenetrable bottom plate and to permit the awl to come to rest when the awl strikes said impenetrable plate, said means being also arranged subsequently to withdraw the awl from the work.
12. A fastening inserting machine having, in combination, an awl, and means for reciprocating the awl including connections arranged to be broken when the awl strikes an impenetrable member back of the work piece, said connections being arranged to become operative later in the cycle of operation of the machine to cause the awl reciprocating means to withdraw the awl from the work piece.
13. A fastening inserting machine having, in combination, an awl, means for reciprocating the awl constructed and arranged to cause the awl to penetrate the bottom of a shoe on a last having an impenetrable bottom plate and to be withdrawn therefrom, said means including a connection arranged to be broken when the awl hits said impenetrable plate and to be remade during the withdrawal movement of the awl reciprocating means so that the latter is effective to withdraw the awl from the shoe bottom.
14. A fastening inserting machine having, in combination, fastening inserting instrumentalities including an awl constructed and arranged to form fastening receiving holes passing completely through a work piece and then to come to rest, whereby the awl measures the thickness of the work piece, and means for feeding a strip of fastening material step by step toward the fastening inserting instrumentalities constructed and arranged to cause the length of each step to be controlled by the thickness of the work piece as measured by the awl.
15. A fastening-inserting machine having, in combination, fastening-inserting instrumentalities including an awl operable to form fastening receiving holes in a work piece the depths of which are determined by resistance encountered by the awl as it completes its passage through the work piece, means for feeding a strip of fastening material toward the fastening inserting instrumentalities, and means for severing pegs from the strip of material, the feeding means being constructed and arranged to cause the length of each peg to be controlled by the distance measured by the awl while passing through the work piece in forming a hole for that peg.
16. A fastening inserting machine having, in combination, fastening inserting instrumentalities including an awl, an awl carrier, means for reciprocating the awl carrier through a path the length of which depends upon the entire thickness of the bottom of a shoe presented to the fastening inserting instrumentalities, and means for presenting fastenings to the fastening inserting instrumentalities arranged to cause the length of each fastening to be controlled by the length of the corresponding reciprocation of the awl carrier.
17. A fastening inserting machine arranged to insert fastenings in the bottoms of shoes mounted on lasts having, in combination, fastening inserting instrumentalities including a bar reciprocable through a path the length of which is determined by the thickness of the bottom of a shoe mounted on a last, means for feeding a strip of fastening material toward the fastening inserting instrumentalities, and connections between the strip feeding means and the reciprocable bar constructed and arranged to cause the length of strip fed to depend upon the length of the reciprocation of said bar.
18. A fastening-inserting machine having, in combination, fastening-inserting instrumentalities including an awl bar, an awl carried thereby and reciprocable with the awl bar through a path the length of which is determined by resistance to the movement of the awl encountered by the awl as it completes its passage through the work piece, a reciprocable feed dog arranged to engage a strip of fastening material and to feed the strip toward the fastening-inserting instrumentalities, and connections between the reciprocable dog and the reciprocable awl bar constructed and arranged to cause the length of the effective strip feeding movement of the dog to depend upon the length of the reciprocation of the awl bar.
19. A fastening inserting machine having, in combination, fastening inserting instrumentalities including an awl arranged to penetrate a work piece and to be stopped by an impenetrable member back of the work piece, and means for supplying to the fastening inserting instrumentalities a fastening the length of which is determined by the depth to which the awl has penetrated the work piece.
20. A fastening inserting machine having, in combination, fastening inserting instrumentalities including an awl arranged to penetrate a work piece thereby forming a fastening receiving hole and to be stopped by an impenetrable member back of the work piece, and means for severing from a strip of fas-

tening material and presenting to the fastening inserting instrumentalities for insertion thereby a fastening the length of which is determined by the thickness of the portion of the work piece in which the awl has formed a hole.

21. A fastening inserting machine having, in combination, fastening inserting instrumentalities including an awl arranged to penetrate a work piece and to be stopped by an impenetrable member back of the work piece, a throat arranged to guide fastenings to the work piece, and means for supplying fastenings to the throat arranged to control the length of each fastening in accordance with the thickness of the portion of the work piece between the throat and said impenetrable member.

22. A fastening inserting machine having, in combination, fastening inserting instrumentalities including an awl arranged to penetrate a work piece and to be stopped by an impenetrable member back of the work piece, a throat, means for supplying fastenings to the throat including means for feeding a strip of fastening material toward the throat, and means for severing fastenings from the strip arranged to control the length of each fastening severed in accordance with the thickness of the portion of the work piece between the throat and said impenetrable member in which the respective fastenings are to be inserted.

23. A fastening inserting machine having, in combination, fastening inserting instrumentalities including a tool acting as an awl and arranged to penetrate a work piece and to be stopped by an impenetrable member back of the work piece and subsequently acting as a driver to insert a fastening in the hole which it has formed in the work piece, a throat, means for severing fastenings from a strip of fastening material, and means for feeding the strip of fastening material to the severing means constructed and arranged to cause the length of each fastening to be determined by the thickness of the portion of the work piece between the throat and the impenetrable member.

24. A fastening inserting machine having, in combination, fastening inserting instrumentalities including an awl arranged to penetrate a work piece and to be stopped by an impenetrable member back of the work piece a throat arranged to guide fastenings to the work piece, means for severing fastenings from a strip of fastening material, and means for feeding the strip of fastening material to the severing means constructed and arranged to cause the length of each fastening to be determined by the thickness of the portion of the work piece between the throat and the impenetrable member.

25. A fastening inserting machine having, in combination, an awl bar arranged for re-

ciprocating movement, an awl carried by the awl bar and arranged to form fastening receiving holes in a work piece presented thereto, means for reciprocating the awl bar thereby thrusting the awl forcibly into the work piece, and connections between the awl bar and said means arranged to permit the awl bar and the awl to come to rest at whatever position they occupy when the awl encounters an impenetrable member by which the work piece is backed up but to permit the means for reciprocating the awl bar to continue its operation.

26. A fastening inserting machine having, in combination, an awl bar arranged for reciprocating movement, an awl carried by the awl bar and arranged to form fastening receiving holes in a workpiece presented thereto, a lever rocked through a definite path to reciprocate the awl bar, and connections between the awl bar and said lever arranged to permit the awl bar and the awl to come to rest when the awl encounters an impenetrable member by which the work piece is backed up but to permit the lever to rock to the end of its path.

27. A fastening inserting machine having, in combination, fastening inserting instrumentalities including an awl, a carrier for the awl, a member detachably connected to the carrier, and means for reciprocating said member, the connections between said member and the awl carrier being constructed and arranged to force the awl into a work piece presented thereto until the awl meets an excessive resistance at which time the connection is temporarily broken so that the awl and the awl carrier may come to rest while said detachably connected member and the reciprocating means therefor continue their movement.

28. A fastening inserting machine having, in combination, fastening inserting instrumentalities including an awl, a carrier for the awl, a member detachably connected to the carrier, and cyclically operated means for reciprocating said member through a definite path, the connections between said member and the awl carrier being constructed and arranged to force the awl into a work piece presented thereto until the awl meets an excessive resistance at which time the connection is broken so that the awl and the awl carrier may come to rest while said detachably connected member continues its movement to the end of its path.

29. A fastening inserting machine having, in combination, fastening inserting instrumentalities including an awl, a member reciprocation of which reciprocates the awl, a latch member connected thereto and provided with a shoulder, a second latch member provided with a shoulder arranged for engagement with the shoulder of the first latch member, means tending yieldingly to hold the two

latch members together with their shoulders in engagement with each other, and means for reciprocating the second latch member.

30. A fastening inserting machine having, in combination, an awl, and means for reciprocating the awl to form fastening receiving openings in a work piece presented thereto, said means including a pair of interengaging latch members constructed and arranged to transmit reciprocating movement to the awl until the awl meets an excessive resistance and then to allow the awl to come to rest, said means being arranged subsequently to withdraw the awl from the work piece.

15 31. A fastening inserting machine having, in combination, an awl, a cam for reciprocating the awl to form fastening receiving openings in a work piece presented thereto, and connections between the cam and the awl including a pair of interengaging latch members constructed and arranged to transmit reciprocating movement to the awl until the awl meets an excessive resistance and then to disengage the latch members thereby allowing the awl to come to rest, said connections being constructed and arranged subsequently to withdraw the awl from the work piece.

20 32. A fastening inserting machine having, in combination, an awl, and means for reciprocating the awl to form fastening receiving openings in a work piece presented thereto, said means including a pair of interengaging latch members constructed and arranged to transmit reciprocating movement to the awl until the awl meets an excessive resistance whereupon one of the shoulders is dragged from the other to allow the awl to come to rest.

25 33. A fastening inserting machine having, in combination, an awl, a cam for reciprocating the awl to form fastening receiving openings in a work piece presented thereto, and connections between the cam and the awl including a pair of interengaging latch members for transmitting reciprocating movement to the awl and so arranged that when the awl meets an excessive resistance the shoulders are dragged one from the other thereby allowing the awl to come to rest, said connections being constructed and arranged to withdraw the awl subsequently from the work piece.

30 34. A fastening inserting machine having, in combination, fastening inserting instrumentalities including an awl, a member reciprocati-

65 ong of which reciprocates the awl, a latch member connected thereto, a second latch member arranged for engagement with the first, means tending yieldingly to hold the two latch members in engagement with each other, and means for reciprocating the second latch member thereby, when the latch members are in engagement, reciprocating the awl.

65 35. A fastening inserting machine having,

in combination, an awl bar, an awl carried thereby and arranged for reciprocating movement with the awl bar to form fastening receiving holes in a work piece presented thereto, a latch member carried by the awl bar, a second latch member mounted for sliding movement on the awl bar and arranged to be secured to the awl bar by the first latch member, means for reciprocating the second latch member to cause the awl to form fastening receiving holes in the work piece, and connections between the two latch members arranged to be broken when the awl meets an excessive resistance so that the awl may come to rest while the second latch member continues its movement toward the work piece, the latch members being arranged also to engage each other during the return stroke of the second latch member so that when the awl is withdrawn from the work piece the mechanism is in condition for operating through another cycle.

70 36. A fastening inserting machine having, in combination, an awl bar, a sleeve slidably mounted thereon, means for reciprocating the sleeve, a latch member pivoted to the sleeve, a second latch member pivoted to the awl bar, means for reciprocating the sleeve through a fixed path of movement, a relatively light spring tending to urge the two latch members into engagement with each other and a heavier spring tending to resist movement of the first latch member in a direction to disengage the latch members from each other.

75 37. A fastening inserting machine having, in combination, an awl bar, an awl carried thereby, a sleeve slidably mounted on the awl bar, means for reciprocating the sleeve, and mechanism for disconnecting the sleeve and the awl bar comprising a latch member pivoted to the sleeve, a second latch member pivoted to the awl bar, a relatively light spring tending to urge the second latch member into engagement with the first and a heavier spring tending to resist movement of the first latch member in a direction to disengage the members from each other, the resistance of said heavier spring being overcome and the latch members disconnected when the awl meets an excessive resistance in penetrating a work piece.

80 38. A fastening inserting machine having, in combination, a cam, a lever continuously rocked by said cam, a reciprocable driver operating member, a sleeve slidably mounted on said member and connected to said lever, a latch operable to secure said sleeve to the driver operating member and a manually operable controller for said latch movement of which is effective to connect and disconnect the latch and the sleeve and thereby to start and stop the driver operating member.

85 39. A fastening inserting machine having, in combination, two levers continuously

- rocked about their respective fulcrums, an awl bar arranged for reciprocation by one of the levers in a path having a variable length, means for feeding a strip of fastening material and for severing fastenings from the strip of material operated by the other lever, and means for causing the length of the fastenings severed to be determined by the length of the reciprocation of the awl bar.
40. A fastening inserting machine having, in combination, an awl bar having a cam surface formed thereon, means for reciprocating the awl bar through a variable path, a lever arranged to be rocked by said cam surface, and means connected to the lever for feeding a strip of fastening material through a distance determined by the extent of the movement of the cam surface on the awl bar.
41. A fastening inserting machine having, in combination, an awl bar, a cam carried by the awl bar, means for reciprocating the awl through a variable path, a lever, a dog carried by the lever and arranged to engage a strip of fastening material, means for moving the lever and the dog bodily to cause the dog to feed the strip of material, and a spring urging one end of the lever into engagement with the awl bar in the path of movement of said cam whereby relative reciprocation of the awl bar and the lever causes the cam to move the dog into and out of engagement with the strip of material and the length of the feeding movement imparted by the dog to the strip of fastening material is dependent upon the length of the path through which the awl bar is reciprocated.
42. A fastening inserting machine having, in combination, an awl bar provided with a cam groove, means for reciprocating the awl bar through a variable path, a lever carrying a dog arranged for feeding engagement with a strip of fastening material and having a tail positioned in the cam groove thereby to rock the lever as the lever is reciprocated relatively to the awl bar moving the dog into and out of strip-feeding position and holding the dog in strip-feeding position for a period dependent upon the length of the reciprocation of the awl bar, and means for moving the lever and the dog lengthwise of the strip while the dog is held in strip-feeding position to feed the strip of fastening material a distance determined by the extent of movement of the awl bar.
43. A fastening inserting machine having, in combination, a throat, a driver reciprocable through said throat, a stationary and a movable shear member having fastening receiving passages therein, the movable shear member being arranged for rocking movement to transfer its fastening-receiving passage from fastening-receiving position in alinement with the passage of the stationary
- shear member to fastening-inserting position in alinement with the path of movement of the driver through the throat, a slide member, strip-feeding means carried thereby and arranged during the first part of the movement of said slide member toward the work piece to feed a strip of fastening material through the shear members, and connections between the slide member and the movable shear member arranged to rock the movable shear member after the conclusion of the strip-feeding movement, thereby severing a fastening from the strip of material and presenting it in fastening-inserted position.
44. A fastening inserting machine having, in combination, a stationary shear member, a movable shear member co-operating therewith, the movable shear member comprising a lever arranged for rocking movement about its fulcrum and being provided with a fastening-receiving passage movable by said rocking movement from fastening-receiving to fastening-inserting position, a slide member, strip-feeding means carried thereby and arranged during the first part of the movement of said slide member toward the work piece to feed a strip of fastening material toward the shear members, and connections between the slide member and the movable shear member arranged to rock the movable shear member about its fulcrum after the conclusion of the strip-feeding movement, thereby severing a fastening from the strip of material and presenting it in fastening-inserting position.
45. A fastening inserting machine having, in combination, an awl operating bar, means for reciprocating said bar through a variable path, a member mounted for reciprocation lengthwise of a strip of fastening material, means for reciprocating said member, a lever fulcrumed to said member, strip engaging means carried by the lever, movable by the rocking of the lever into and out of engagement with the strip of fastening material and arranged as said member is reciprocated to move freely over the fastening material in one direction and to feed the strip of fastening material in the other direction during such portion of its movement in that direction as the position of the lever permits its engagement with the strip of material, and a cam carried by the awl bar in the path of movement of said lever to rock the lever and thereby to move the strip engaging means into and out of strip-engaging position.
46. A fastening inserting machine having, in combination, an awl bar, an awl carried thereby, means for reciprocating the awl bar through a path dependent upon the depth which the awl penetrates a work piece presented thereto, a member mounted for reciprocating movement lengthwise of the awl bar, means for reciprocating said member, a lever

fulcrumed to said member, a dog carried by the lever, movable by the rocking of the lever into and out of engagement with a strip of fastening material and arranged as said member is reciprocated to slide freely over the fastening material in one direction and to feed the strip of fastening material in the other direction during such portion of its movement in that direction as the position of the lever permits engagement of the dog with the strip of material, and a cam carried by the awl bar in the path of movement of said lever to rock the lever and thereby to move the dog into and out of strip-engaging position.

47. A fastening-inserting machine having, in combination, a nozzle, an awl, operating means therefor, and connections between the awl and its operating means constructed and arranged to thrust the awl forcibly into a work piece presented thereto but to permit the awl to come to rest relatively to the nozzle in each cycle of operation when it meets an excessive resistance and later in the cycle to withdraw the awl from the work, and means for inserting a fastening in the hole formed in the work piece by the awl.

48. A fastening-inserting machine having, in combination, means for measuring the thickness of the bottom of a shoe mounted on a last including a measuring member and operating mechanism therefor constructed and arranged to give way when the measuring member meets an excessive resistance, and means for inserting in the bottom of the shoe fastenings corresponding to the measured thickness of the shoe bottom.

49. A fastening-inserting machine having, in combination, an awl, means for reciprocating the awl constructed and arranged to thrust the awl into the bottom of a shoe mounted on a last and to permit the awl to be arrested when the awl strikes a metal bottom plate on the last, said means including a connection constructed and arranged to break when the awl strikes the metal bottom plate of the last, and means for inserting fastenings in the holes formed by the awl in the shoe bottom.

50. A fastening-inserting machine having, in combination, an awl, means for reciprocating the awl including a connection arranged to give way when the awl meets an excessive resistance in its work penetrating movement, means for severing fastenings from a strip of fastening material, and means for feeding the strip of fastening material controlled by the depth to which the awl pierces the work piece so that each fastening severed will be of a length corresponding to the depth to which the awl pierces the work piece at the point where it is to be inserted.

51. A fastening-inserting machine having, in combination, an awl, means for reciprocating the awl including a connection ar-

ranged to give way when the awl hits an impenetrable member back of the work piece, means for severing fastenings from a strip of fastening material, and means for feeding the strip of fastening material controlled by the thickness of the work piece so that each fastening severed will be of a length corresponding to the thickness of the work piece at the point where it is to be inserted.

In testimony whereof I have signed my name to this specification.

FRED C. EASTMAN.
